UNITED STATES PATENT OFFICE.

JOHN S. McCHESNEY, OF CHICAGO, ILLINOIS, ASSIGNOR TO J. S. McCHESNEY & CO., OF CHICAGO, ILLINOIS, A CORPORATION OF ILLINOIS.

BROOM-FILLER-ASSEMBLING MACHINE.

1,186,810.

Specification of Letters Patent. Patented June 13, 1916.

Application filed August 27, 1914. Serial No. 858,808.

To all whom it may concern:

Be it known that I, JOHN S. McCHESNEY, citizen of the United States, residing at Chicago, in the county of Cook and State of Illinois, have invented a certain new and useful Improvement in Broom-Filler-Assembling Machines, of which the following is a full, clear, concise, and exact description, reference being had to the accompanying drawings, forming a part of this specification.

My invention relates to the manufacture of brooms and has for its general object the provision of a broom filler assembling machine whose purpose is to permit the ready application of previously formed bands to bundles of broom straw. The machine of my invention is of particular service in preparing bundles of broom straw with encircling bands which are subsequently to be subject to a collapsing operation that is preferably effected by a distinct mechanism but to the employment of which distinct mechanism the invention is not to be limited.

In practising my invention I employ a chuck for effecting the initial assembly of broom straw into a bundle and having a portion of its wall arranged to be opened and closed, the chuck when closed permitting the broom bands to be alined therewith in position to enable the passage therethrough of the butt end of a bundle of broom straw, the chuck being opened after the bands or rings have been positioned about the broom straw to permit of the transfer of the banded straw to another machine where the bands are collapsed into permanent clamping engagement with the straw, the resulting product being a permanently assembled bundle of straw itself forming a broom or capable of being combined with a handle to produce a handled broom.

In practising my present invention I employ mechanism for feeding or permitting movement of the bands into alinement with the chuck; mechanism for opening and closing the chuck; and actuating mechanism common to the aforesaid mechanisms and serving to operate the same in orderly sequence. The actuating mechanism which I prefer to employ is one that includes an operating treadle but I do not wish to be limited to the source of power nor to the

means for transmitting the same to the band feeding and chuck operating mechanisms.

I will explain my invention more fully by reference to the accompanying drawings showing the preferred embodiment thereof and in which—

Figure 1 is a side view of a machine equipped in accordance with the invention; Fig. 2 is a sectional plan view on line 2 2 of Fig. 1; Fig. 3 is a side view of some of the mechanism illustrated in Fig. 1; Fig. 4 is a sectional view on line 4 4 of Fig. 7; Fig. 5 is a perspective view of a partially formed product as it leaves the machine of the invention preparatory to a band collapsing operation; Fig. 6 is a view on line 6 6 of Fig. 7; Fig. 7 is a view on line 7 7 of Fig. 6; Fig. 7^a is a detail illustrating the positions of some of the parts as they appear in Fig. 7; Fig. 8 is a view on line 8 8 of Fig. 9; Fig. 9 is a view on line 9 9 of Fig. 8.

Like parts are indicated by similar characters of reference throughout the different figures.

The broom straw is preferably temporarily assembled by hand in quantities just sufficient to constitute the desired brooms. The manually assembled bundles of straw are inserted endwise within a chuck 1 of bell shape, the stem of the chuck having transverse spaces or grooves 2 therein for the reception of rings or bands 3 which are preferably completely formed and are desirably disposed within fixed range of the chuck by means of ring holders or magazine structures 4 that are preferably removably supported at 4¹, Fig. 1, each groove 2 having but one magazine individual thereto, these magazines being angularly separated as indicated most clearly in Figs. 1 and 7. Each magazine overlies the ledges 5 which margin a groove 6, there being thus two grooves 6 which are angularly separated, the bottom ring in each vertically alined pile of rings resting upon the top surfaces of the ledges 5 margining the groove 6 individual to such pile. The top surfaces of the rear pair of ledges 5 are in the same plane with the bottom of the upper space or groove 2 while the top surfaces of the remaining pair of ledges 5 are in the same plane with the bottom of the lower space or groove 2.

A pusher 7 is individual to each groove 2 and slides upon the ledges 5 also indi-

vidual to such groove. These pushers 7 are designed for simultaneous operation and in their outermost positions are behind the rings that rest upon the ledges 5. As these pushers are thrust inwardly they carry with them the lowermost rings from their places beneath their magazines, the pushers in their innermost positions placing these rings in alinement with the bore of the chuck (now closed), the rings entering this position by passing through the grooves or openings 2 in the chuck. After a pair of rings are thus alined with the chuck, a previously gathered bundle of straw, which is of sufficient amount to form the desired broom, is passed downwardly, butt end first, through the bore of the chuck and the two rings which temporarily take part in defining the bore of the chuck. After the butt end of a bundle 20 of straw has thus been passed through a pair of rings the chuck is opened, a half 1¹ of the chuck being in hinged connection with the remainder, as indicated most clearly in Figs. 3, 7, 7^a, 8 and 9. After the chuck 25 has been opened the banded bundle of straw may be removed to be subject to the operation of a ring collapsing machine to bring about a permanent assembly of the straw. In accordance with my present invention 30 the operation of the pushers and the opening and closing of the chuck are so relatively timed that these operations are bound to occur in predetermined and fixed order and to this end I prefer to employ the form of 35 mechanism now to be specifically described.

The power for operating the machine is desirably applied by the foot of the operator to the treadle 8 having a fixed fulcrum at 9 and connected at an intermediate portion 40 thereof with the lower end of link 10 that is pivotally connected at its upper end with a collar 11 arranged to slide vertically upon an upright guide rod 12 whose upper end carries an adjustable catch 13 that defines 45 the extent to which the butt end of a bundle of straw may be inserted within the chuck 1. A spring 14, surrounding the guide rod 12, serves normally to position the treadle and collar in the locations for these elements 50 illustrated in Fig. 1. Levers 15 (each individual to a pusher 7) are fulcrumed at their lower ends and carry rollers 16 at their upper ends which are received between the sides of forked lugs 17 that are secured to 55 the bottoms of the pushers 7. Intermediate portions of the levers 15 are connected by links 18 with the sleeve or collar 11 whereby the levers 15 are moved outwardly when the treadle is depressed against the force of the 60 spring 14 to position the pushers 7 to the rear of and in line with the lowermost bands 3 that are resting upon the pairs of ledges 5 that are individual to the vertically alined grooves 2 and also to open the chuck. When 65 the treadle is released the spring 14, in re-

storing the parts to the positions illustrated in Fig. 1, forces inward movement of the pushers 7 whereby two rings are removed from the region of their magazines into alinement with the bore of the chuck as 70 illustrated most clearly in Fig. 6, the chuck being also closed during this inward movement of the pushers.

The swinging section 1¹ of the chuck is provided with a crank arm 19 to which motion may be imparted through pitman mechanism that is operatively connected at one end with the outer end of the crank 19 and at its other end with the rear one of the two levers 15. When the rear pusher 7 that 75 is individual to the rear lever 15 is moved inwardly upon the inward movement of this lever the crank 19 is turned to close the section 1¹ of the chuck 1, this closure being desirably completed before both bands 80 which are being pushed by both pushers have been finally positioned in alinement with the bore of the chuck. In order that the chuck may be closed before the two 85 rings are alined therewith, the pitman mechanism preferably includes a rod 20 free to move within the bore of a cross head or guiding sleeve 21 carried upon the rear lever 15 by means of a universal joint 22. The cross head sleeve 21 is disposed between collars 23 that are adjustably fixed upon the rod 20, springs 24 and 25 being located between the sleeve 21 and the collars 23 as indicated most clearly in Fig. 9. As the rear lever 15 is moved inwardly it causes the 90 sleeve 21 to press upon the spring 25, the pressure thus exerted being transmitted through the forward collar 23 and the rod 20 to the crank arm 19 whereby the section 95 1¹ of the chuck is ultimately closed. The closure of the chuck, however, is completed before the levers 15 have been moved to their innermost positions, continued inward movement of the levers 15 being permitted, in order to place the two rings in alinement 100 with the closed chuck, by means of the spring 25 that will then yield sufficiently for this purpose. The chuck section 1¹ having been closed before the rings are located within the chuck, means may be employed 105 whereby the front pusher 7 may be brought into position to hold the chuck closed when the inward movements of the pushers have been completed whereby the closure of the 110 chuck is so firm that the subsequent insertion of a bundle of broom straw will not open the chuck whereby the alinement of the broom bands with the bore of the closed 115 chuck cannot be disturbed while a bundle of straw is being inserted within the closed 120 chuck, it being assumed that the treadle is in its released position, it being understood that it is necessary to release the treadle in order to permit the spring 14 to move the 125 pushers inwardly to close the chuck. The 130

means by which the chuck is maintained in firmly closed position desirably resides in a catch 26 projecting from the inner end of the front pusher 7 and engaging a flat continuation 27 of the chuck section 1¹, indicated most clearly in Fig. 7^a. By depressing the treadle 8 the pushers 7 may be withdrawn to their rearmost positions, as previously described, the rear movement of the 10 pushers being accompanied by an opening action of the chuck which is effected by the pressure of the sliding collar or cross head 21 upon the spring 24, the pressure being transmitted from the spring 24 through a 15 collar 23 to the rod 20. The chuck is opened when the lug 28 engages the stop 29, this engagement occurring before the pushers 7 are in their rearmost positions. Continued movement to the rear, after the complete 20 opening of the chuck, is permitted by the spring 24 which may be further compressed after the chuck has been completely opened to permit of the further rearward movement of the levers 15.

25 It will thus be seen that I have provided mechanism whereby the opening and closing of the chuck is timed to occur in proper relation to the forward and rearward movement of the pushers and while I prefer to 30 employ the mechanism illustrated for accomplishing this result I do not wish to be limited thereto as changes may readily be made without departing from the spirit of the invention.

35 While I prefer to employ means for feeding two bands to the chuck I do not wish to be limited to the feeding of a plurality of bands to the chuck at a time, it being obvious that my invention is capable of use when 40 one or more bands are to be fed into place.

Having thus described my invention I claim as new and desire to secure by Letters Patent the following:

1. A broom filler assembling machine including a chuck for effecting the initial assembly of broom straw into bundles and having a portion of its wall arranged to be opened and closed; mechanism for effecting the feeding of bands into alinement with the chuck; mechanism for opening and closing the chuck; and controlling mechanism common to the aforesaid mechanisms to effect their operation in orderly sequence, the mechanism for opening and closing the 55 chuck including a crank arm connected with

the movable wall portion of the chuck, a cross head moving with the band feeder, a pitman rod with respect to which the cross head is movable, and springs interposed between the cross head and portions fixed upon the pitman rod, one spring serving to permit closure of the chuck before the bands are fed into position and the other spring permitting opening of the chuck before the band feeder has been completely withdrawn. 65

2. A broom filler assembling machine including a chuck for effecting the initial assembly of broom straw into bundles and having a portion of its wall arranged to be opened and closed; mechanism for effecting 70 the feeding of bands into alinement with the chuck; mechanism for opening and closing the chuck; and controlling mechanism common to the aforesaid mechanisms to effect their operation in orderly sequence, the 75 mechanism for opening and closing the chuck including a crank arm connected with the movable wall portion of the chuck, a cross head moving with the band feeder, a pitman rod with respect to which the cross 80 head is movable, and springs interposed between the cross head and portions fixed upon the pitman rod, one spring serving to permit closure of the chuck before the bands are fed into position and the other spring 85 permitting opening of the chuck before the band feeder has been completely withdrawn, the feeder carrying a portion which is brought into position to maintain the chuck closed when the bands are fed into place. 90

3. A broom filler assembling machine including a chuck for effecting the initial assembly of broom straw into bundles and having a portion of its wall arranged to be opened and closed; mechanism for effecting 95 the feeding of bands into alinement with the chuck; mechanism for opening and closing the chuck; and controlling mechanism common to the aforesaid mechanisms to effect their operation in orderly sequence, the 100 feeder carrying a portion which is brought into position to maintain the chuck closed when the bands are fed into place.

In witness whereof I hereunto subscribe my name this twentieth day of August, 105
A. D. 1914.

JOHN S. McCHESNEY.
